UNITED STATES PATENT OFFICE.

WILLIAM HENRY BROOKS, OF TORONTO, ONTARIO, CANADA.

SKYLIGHT.

1,158,626.

Specification of Letters Patent.

Patented Nov. 2, 1915.

Application filed June 21, 1915. Serial No. 35,268.

To all whom it may concern:

Be it known that I, WILLIAM HENRY BROOKS, of the city of Toronto, in the county of York, in the Province of Ontario, Canada, have invented certain new and useful Improvements in Skylights, of which the following is the specification.

My invention relates to improvements in sky lights and the object of the invention is to devise a sky light so constructed as to be capable of ready adjustment to fit any size of wooden curb extending around the sky light opening in a roof and it consists essentially of a sheet metal curb frame provided with side and end sections forming the inclined sky light sides, each section being divided into two members, one member being stationary and formed integral with the metal curb frame and forming a guideway extending parallel with each of the curb sides and the other member slidably held in the bottom of such guideway, a telescopic connection between the upper portion of the stationary and slidable members forming the side sections of the sky light, a slide-way forming a bridging bar located at each end of such side sections and connecting such side sections together and slidable means for supporting the upper portion of the members of the end sections in such slide-ways as herein-after more particularly explained by the following specification.

Figure 1, is a perspective view of my sky light with the glazing removed. Fig. 2, is a plan view of the sky light as shown in Fig. 1. Fig. 3, is a perspective detail of the sky light with the slidable section members removed. Fig. 4, is a perspective view of my sky light showing the movable section members adjusted ready for fitting a sky light having a smaller curb. Fig. 5, is an enlarged longitudinal sectional view through the sky light on line x^4-y^4 Fig. 2. Fig. 6, is an enlarged sectional view on line $x-y$ Fig. 2. Fig. 7, is an enlarged sectional view on line $x'-y'$ Fig. 2. Fig. 8, is a sectional detail through one of the hips of the sky light on line x^2-y^2 Fig. 2. Fig. 9, is a plan section on line x^3-y^3 Fig. 6. Fig. 10, is a perspective detail of one of

the movable members of the side section of the sky light. Fig. 11, is a perspective detail of one of the movable members of an end section of the sky light.

55

In the drawings like letters of reference indicate corresponding parts in each figure.

1 indicates the ordinary wooden curb which is carried by the roof of a building around a sky light opening formed therein. 60

2 indicates my metal curb frame comprising a vertical wall portion 3 and an inwardly inclined wall portion 4. It will be understood that the curb frame 2 is made of such a size as to fit the largest size curb 65

5 and 6 indicate the side portions of the metal curb frame and 7 and 8 the end portions. The upper edge of the inclined wall portion 4 of the side curb frame portions 5 70 and 6 and end curb frame portions 7 and 8 are each provided with extensions 5 $\times$, 6 $\times$, 7 $\times$ and 8 $\times$. Each portion 5 $\times$, 6 $\times$, 7 $\times$ and 8 $\times$ is provided with a longitudinal slot 9. Below the longitudinal slot 9 of the side portions 75 5 $\times$ and 6 $\times$ such extension portions 5 $\times$ and 6 $\times$ are cut shorter than the side portions 5 and 6 of the curb frame. Similarly the portions 7 $\times$ and 8 $\times$ below the slot 9 are cut shorter than the portions 7 and 8. Each of 80 such portions extending beneath the slot 9 is bent upwardly at 10 and 11 in step form so as to form a series of ledges 12, 13 and 14.

15 indicates a hip portion extending upwardly at an incline from one end of each 85 portion 7 $\times$ and 8 $\times$ and secured at its lower end to such portions. The upper end of the hip portion 15 is provided with an angle bracket 15 $\times$ formed integral therewith. Such bracket portion 15 $\times$ comprises a vertical wall 15' and a horizontal wall 15 $\circ$. 90

16 indicates a hip portion extending upwardly at an incline direction from one end of the portion 5 $\times$ and 16 $\times$ a similar portion extending from the opposite end of 95 the portion 6 $\times$. The upper end of the hip portion 16 $\times$ is provided with a horizontal extension 17 extending longitudinally of the sky light. The portion 17 is formed in cross section as shown clearly in Fig. 7 of 100 the drawings, such portion comprising a vertical wall portion 17', the upper edge of

which is turned inwardly and upwardly to form an inwardly extending hollow flange 17², the upper wall portion 17³ of such hollow flange extending outwardly and provided at its extreme outer end with a down-turned portion 17⁴ forming a longitudinal guideway space between such down-turned portion 17⁴ and the vertical wall 17' of the portion 17.

10 17^x indicates a portion similar to the portion 17, with the exception that the parts corresponding to the parts 17', 17² and 17³ are bent into contact to form a solid instead of a hollow flange.

15 18 and 18^x indicate the movable members of the side sections of the sky light. These members comprise a hip portion 19 and an upper horizontal portion 20 and a lower horizontal portion 21. The upper horizontal portion is formed with a vertical wall portion 20', the upper edge of which is bent backwardly on itself so as to form an inwardly extending flange 20². In the case of the member 18 the flange 20² is formed hollow similar to the flange 17² hereinbefore described and into which the flange 17^x slidably fits. In the case of the flange 20² of the member 18^x the flange is formed solid and fits into the flange 17^x hereinbefore described.

20 The edge of the portion forming the rib 20² extends outwardly and is provided at its outer end with a down-turned portion 20³ fitting against the inner face of the down-turned portion 17⁴ so as to leave a space between such portion 20³ and the vertical wall portion 20', for a purpose which will hereinafter appear. The lower horizontal portion 21 is provided with stepped portions 22, 23 and 24 fitting against the step portions 12, 13 and 14 of the portions 5^x and 6^x.

It will be noticed particularly on reference to Fig. 7 that the turned-over extensions 5^x and 6^x are spaced apart from the inclined wall portions 4 of the curb portions 5 and 6. The inner edges of the portions 21 are turned inwardly in hook form in cross section as shown clearly in Fig. 7 at 25 so as to extend through the slots 9 of the portions 5^x and 6^x so as to be slidable therein. The outer edge of the portion 24 is also turned down and around the stepped portion 14 of each of the portions 5^x and 6^x. By this means a rigid slidable connection is formed between the portion 21 and the portions 5^x and 6^x. 26 indicates a dividing bar for each of the side sections of the sky light. The bar 26 is inverted T-shaped in cross section and is provided at its upper end with a vertical portion 27, the upper edge of which extends into the space between the down-turned portion 20³ and the vertical portion 20', the upper end of the bar 26 resting upon the ledge 28 forming part of the portions 20 and 17. 29 indicates

a drip trough which is also formed integral with the portions 20 and 17. 30 indicates a guiding flange secured to the inner edge of the drip trough 29, such flange being hook shaped in cross section. 31 indicates a hook member secured to the dividing bar 26 and interlocking with the hook portion of the flange 29. 31^x indicates a similar member to the flange 29. The member 31^x is secured to the up-turned portion of the extensions 5^x and 6^x located between the ledges 12 and 13. 32 indicates a hook member also secured to the dividing bar 26 and interlocking with the hook-shaped flange 31^x. By this means the dividing bar 26 may be adjusted longitudinally of the side sections of the sky light to any position required. 32 indicates an upwardly extending plate projection formed integral with the hip member 15. 34 indicates an angle bar resting at its ends upon the angle brackets 15^x. 35 indicate the adjustable members of the end sections of the sky light. The adjustable portions 35 comprise a hip portion 36, the vertical flange portion of which fits against the hip portion 16^x of the stationary member forming the side sections of the sky light. 37 indicates an adjustable portion formed integral with the hip portion 36 and fitting the portions 7^x and 8^x of the stationary portions of the end sections of the sky light. The portions 37 are also provided with hook flanges 39 fitting into the longitudinal slots 9 of such portions 7^x and 8^x so as to be slidable longitudinally therein. The upper end of the hip portion 36 is provided with a vertical plate extension 36^x for a purpose which will hereinafter appear. 39^x indicate bars forming guideways secured to the angle bars 34. The bars 39^x are provided with slotted front opening 40 extending from end to end of the same. The plate extensions 33 and 36^x rest against the outer face of the bars 39^x. 41 indicate slide pieces held within the bars 39^x so as to slide freely therein. 42 indicate bolts having countersunk heads inserted in the plate 41 and extending through the vertical plate portions 33 and 36^x. 43 indicate nuts threaded on to the bolts 42 against the outer face of the plate extensions 33 and 36^x. By this means the plates 33 and 36^x, guide bar 39^x and plate 41 are clamped together so as to hold them in any position desired. 44 indicate the dividing bars for the end sections of the sky light. The lower ends of the dividing bars are connected to the horizontal portion 37 of the adjustable member in a similar way to that described in connection with the dividing bar 26. The upper end of the dividing bar 44, however, is provided with an upwardly extending plate extension 45 fitting against the outer face of the guide bar 39^x. 46 indicates a plate slidably held within the guide bar 39^x and provided with

a bolt 42^x extending through such plate and through the plate extension 45 and provided at its outer end with a clamping nut 45^x.

15⁵ indicates an orifice in the portion 15' 5 of each bracket 15^x (see Fig. 3).

47 indicates a series of orifices formed in the portion 17' and 20'.

47^x indicates an orifice formed in the outer end of each portion 17', 17^x and 20.

10 48 indicates an orifice formed in the end of the portion 17^x.

49 indicates a bolt extending through one of the orifices 47 alined with the orifice 48.

15 50 indicates a bolt extending through each orifice 47^x and the orifice 15⁵.

In fitting my sky light to a curb the bolts 15⁵ and 49 are withdrawn and the bolts and nuts 43 loosened. The removable members 18, 18^x and 35 are then adjusted as shown in 20 Fig. 4 to form a sky light of the required size. The curb frame is then cut to the corresponding size as indicated by dotted lines in Fig. 4, the cut ends being fastened together by any suitable means. The bolts 18, 25 18^x and 35 are then replaced so as to secure the parts together.

What I claim as my invention is.

1. In a sky light, the combination with the curb frame and side sections of the sky light, of a bridge bar extending between the ends of the opposing side sky light sections and end sky light sections divided on a vertical plane to form two members, each comprising a bottom bar member and an inclined hip member, the bottom bar of one member being connected in a stationary position to the curb frame and the bottom bar of the other member slidably connected to the bottom bar connected to the curb frame, and 40 means for adjustably connecting the upper ends of the hip portions to the bridge bar.

2. In a sky light, the combination with

the curb frame and side sections of the sky light, of an end section adjustably carried by the curb frame between the side sections and provided with upwardly extending hip portions, a bridge bar having a guideway carried by and extending between the side sections, vertical plates forming the upper ends of the hip portions and bearing against the 45 face of the bridge bar, and means extending from the plates into the guideway bar for locking the plates in any desired position longitudinally of the guideway of the bridge bar.

55 3. In a sky light, the combination with the curb frame and side sections of the sky light, of end sections comprising two portions adjustably carried by the curb frame and provided with upwardly extending hip 60 portions, vertical plates forming the upper ends of the hip portions, a bridge bar having horizontal edge guideways, plates slidably held in the guideways of the bridge bar, and clamping screws extending through the 65 plates and plate ends of the hips.

4. In a sky light, the combination with the curb frame having the upper inner edges thereof turned back upon themselves and longitudinally slotted to form the bottom 70 bar of the stationary member of each sky light section, a hip bar extending upwardly from one end of such bottom bar, an adjustable sky light section member provided with a bottom bar having an inturned inner edge 75 engaging the aforesaid slot, a hip bar extending upwardly from the outer end of such adjustable bar, and means for connecting the hip bars together.
